(57) **CLAIM**

The ornamental design for a razor package, as shown and described.

DESCRIPTION

FIG. 1 is a perspective view of a first embodiment of a razor package, showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is an alternate perspective view thereof;

FIG. 9 is perspective view of a second embodiment of a razor package, showing my new design in a partially open configuration;

FIG. 10 is a front view thereof;

FIG. 11 is a back view thereof;

FIG. 12 is a right side view thereof;

FIG. 13 is a left side view thereof;

FIG. 14 is a top view thereof;

FIG. 15 is a bottom view thereof;

FIG. 16 is an alternate perspective view thereof;

FIG. 17 is perspective view of a third embodiment of a razor package, showing my new design in an open configuration;

FIG. 18 is a front view thereof;

FIG. 19 is a back view thereof;

FIG. 20 is a right side view thereof;

FIG. 21 is a left side view thereof;

FIG. 22 is a top view thereof;

FIG. 23 is a bottom view thereof; and,

FIG. 24 is an alternate perspective view thereof.

(Continued)

The short-dash broken lines are shown for the purpose of illustrating parts of the article that form no part of the claimed design. The long-dash lines represent perforations that form a part of the claimed design.
